ATTORNEY

UNITED STATES PATENT OFFICE.

WILLIAM R. THIGPEN, OF FAYETTEVILLE, NORTH CAROLINA, ASSIGNOR TO DRAPER CORPORATION, OF HOPEDALE, MASSACHUSETTS, A CORPORATION OF MAINE.

TENSION DEVICE FOR LOOM SHUTTLES.

Application filed June 4, 1924. Serial No. 717,869.

To all whom it may concern:

Be it known that I, WILLIAM R. THIGPEN, a citizen of the United States, and a resident of Fayetteville, in the county of Cum-
5 berland and State of North Carolina, have invented an Improvement in Tension De-
vices for Loom Shuttles, of which the fol-
lowing description, in connection with the
accompanying drawings, is a specification,
10 like characters on the drawings represent-
ing like parts.

This invention relates to loom shuttles
and more particularly to loom shuttles of
the automatic filling replenishing type in
15 which the shuttle is provided with means
for imparting suitable tension to the filling
or yarn as it is drawn from the filling car-
rier or bobbin.

In weaving with certain characters or
20 kinds of filling it is desirable that the filling
be laid in the shed under tension, the
desired degree of which is not usually im-
parted by the ordinary filling replenishing
25 shuttle. As the filling is withdrawn from
the shuttle during its flight it will swirl or
take a circular course about the end of the
filling carrier or bobbin and be thrown from
30 control of the tensioning means located as
heretofore either on the threading block in
the thread passage, or at a point forward
thereof. One of the features of the present
35 invention therefore consists of a tension de-
vice which extends in the bobbin chamber
of the shuttle closely adjacent to and inclos-
ing the end of the filling carrier or bobbin,
the tensioning end portions of the tension
40 device being located rearwardly of the
threading block and between it and the end
of the filling carrier or bobbin.

In accordance with the present invention,
the tension device is preferably formed of
30 sheet metal having its main body portion se-
cured in fixed position in the shuttle and ex-
tending in the bobbin chamber to inclose the
end of the filling carrier or bobbin from
which the yarn is drawn during weaving.
35 The adjacent ends of the spring tension de-
vice are located rearwardly of the thread-
ing block and beneath such ends of the
spring tension members a support is pro-
vided in the bobbin chamber for prevent-
40 ing downward displacement of the ends of
the spring tension members either during
use or during filling replenishment, and
since the character of the yarn or filling may
45 be changed from time to time, provision is
made for adjustment of the tension mem-
bers, in order to apply varying degrees of
frictional resistance to the movement of the
filling between said members.

The novel characteristics and new fea-
50 tures and combination of parts will best be
made clear from the following description
and the accompanying drawings of one good
form of a shuttle provided with the present
invention.

In the drawings:

Fig. 1 is a perspective view of the thread-
ing end portion of a shuttle, showing suffi-
cient thereof to make clear the association of
the present invention therewith;

Fig. 2 is a plan view of the construction
shown by Fig. 1;

Fig. 3 is a section of the shuttle substan-
tially on the line 3—3 of Fig. 2;

Fig. 4 is a perspective view of the thread-
ing block removed from the shuttle, a por-
tion of the block being cut away;

Fig. 5 is a plan view of a modification of
the invention; and

Fig. 6 is a detail perspective view of one
of the spring members of the modified form
of tension device shown by Fig. 5.

In weaving with certain kinds or char-
acters of filling it is desirable that the fill-
ing be laid in the shed under tension, the
desired degree of which is not usually im-
parted by the ordinary filling replenishing
55 shuttle. As the filling is withdrawn from
the shuttle during its flight it will swirl or
take a circular course about the end of the
filling carrier or bobbin and be thrown from
control of the tensioning means located as
60 heretofore either on the threading block in
the thread passage, or at a point forward
thereof. One of the features of the present
invention therefore consists of a tension de-
vice which extends in the bobbin chamber
65 of the shuttle closely adjacent to and inclos-
ing the end of the filling carrier or bobbin,
the tensioning end portions of the tension
device being located rearwardly of the
threading block and between it and the end
70 of the filling carrier or bobbin.

In that type of shuttle wherein the fill-
ing carrier is ejected when the filling is ex-
hausted or substantially exhausted and a
95 full filling carrier is placed in the shuttle,
it is desirable that the tensioning device,
more especially the filling engaging end por-
tions thereof, shall be so supported that
should the incoming filling carrier touch the
100 tensioning device, it will not be deflected
from its operative position, but, on the other
hand, would rather deflect the filling carrier
itself into its proper position in the shuttle,
and another feature of the present inven-
105 tion therefore consists in forming the ten-
sioning device of metal plates which have
the body portion thereof secured to the loom

shuttle and the ends brought together in the bobbin chamber to inclose the end of the filling carrier or bobbin and rest upon a shelf or support beneath.

5 The shuttle 1 is formed as usual with a bobbin chamber 2 having a bottom opening 3 through which the filling carrier in the shuttle may be ejected on replenishment of filling. In the bobbin chamber 2 of the 10 shuttle the filling carrier or bobbin 4 on which the filling 5 is wound, is supported by any appropriate means now well understood in the art.

Frontward of the end of the filling carrier or bobbin 4 the body of the shuttle is provided with a threading block receiving recess 6, Fig. 3, in which is secured the threading block 7, which may be of usual or any preferred construction adapted for 20 the automatic threading of the shuttle when the latter is picked after the replenishing operation.

The threading block 7 is secured in its operative position in the chamber 6 by the 25 securing bolt 8 which passes laterally through the walls of the shuttle and through a hole in the block 7, and the latter may be provided with a downwardly extending lug 9 to assist in maintaining the threading 30 block in its position, as usual.

As shown in Figs. 1, 2 and 3, the tensioning device comprises the metal springs 10 which may be secured in the bobbin chamber of the shuttle by pins or studs 11. Each 35 of the spring plates 10 extends forwardly in the bobbin chamber, as indicated in Figs. 1 and 2, and at their front end portions, such spring plates converge towards each other, as indicated at 12, at which point 40 they approach the end of the filling carrier or bobbin 4 and inclose the same within the bobbin chamber. At their forward extremities the spring plates 10 are brought together, as indicated at 13, to form a passageway for the filling as it unwinds from 45 the filling carrier or bobbin and passes frontward towards and through the thread passage of the threading block. In order that the ends of the plates 10 may act with 50 the desired tension upon the yarn or filling and in accordance with the character or size thereof, the springs are under the control of regulating means for adjusting their frictional engagement with the filling passing between them. As indicated in Figs. 55 1 and 2, an adjusting screw 14 is passed through the side walls of the shuttle and the ends of the respective screws bear upon the spring plates 10 preferably at a point 60 where said plates curve and converge frontward to enclose the end of the filling carrier or bobbin, the construction being such that upon manipulation of the adjusting screws 14, the tensional energy of the spring mem-

bers 10 upon the filling may be regulated as 65 desired.

When the full or wound filling carrier is placed in the bobbin chamber on automatic replenishment of filling, and the shuttle is picked from the replenishing box, it is 70 desirable that the filling be directed properly to the thread passage of the threading block and between the ends of the spring tensioning members. To this end each of the upper edge portions 15 of the spring plates 10, where they converge, incline downwardly to a slight extent, shown in Fig. 3, 75 so that when the fresh filling carrier has been placed within the shuttle and the shuttle is picked, the swirling or circularly moving filling will be directed by the inclined upper edges 15 of the spring tensioning plates not only to the nip between the plates themselves but also into the thread passage of the threading block. By making the upper edges 15 of the spring tensioning plates slightly downwardly inclined, the incoming filling carrier on replenishment of filling will more effectively move the yielding portions of the spring tensioning plates 80 should the end of the filling carrier strike either.

Since the spring tensioning plates are located within the bobbin chamber and the ends thereof are disposed between the end of the filling carrier and the threading block, or rearward of the latter, it is desirable that the ends of the spring tensioning plates be sustained from displacement downwardly 95 should a filling carrier strike either plate on filling replenishment. As shown in the present instance of the invention, therefore, the shuttle is provided with a shelf or support which extends under the end portions of the spring tensioning members. In the present instance such shelf or support consists of a plate 16 which extends into the threading block receiving chamber 6 and preferably beneath the threading block 7, 100 where it is provided with an opening 17 through which the stud or lug 9 of the threading block is positioned to thereby maintain the shelf or support in position when the threading block is secured in the thread block receiving chamber 6. 110

As indicated in Figs. 2 and 4, it will be noted that the portion of the shelf or support 16 which extends into the bobbin chamber has a rounded contour at 18 directly in front of the filling carrier or bobbin, the construction being such that while such shelf or support 16 thus affords a good practical form of means of preventing deflection of the spring tensioning members downwardly, 115 it in no way interferes with the replenishing operation.

The threading block 7, as indicated more clearly in Fig. 4, has the longitudinally ex-

tending thread passage 19 which may be of usual form, and rearwardly thereof the threading block is provided with the lugs 20 separated from the rear wall of the threading block, and between such wall and the lugs 20 there is supported a bridge 21 preferably formed of metal and having its top surface below the top edge 15 of the spring tensioning members, and preferably in line 10 with the central longitudinal axis of the bobbin or filling carrier 4, so that as the filling unwinds from the filling carrier it will be directed between the ends of the spring tensioning members over the bridge 15 21 and through the thread passage to the side delivery eye 22.

In Figs. 5 and 6 a slightly modified form of the spring tensioning members is shown, wherein each of the tensioning members 20 comprises a plate 23 having a frontwardly extending portion 24 at the side of the threading block 7, through which portions the threading block securing bolt 8 may be passed, in order to hold the spring tensioning plates in operative position. In the construction shown by Figs. 5 and 6, the part 24 of the plate 23 is provided with an opening 25 as a convenient means for securing the tensioning plates into the shuttle by the block securing bolt 8. The portion 23 of each of the spring tensioning plates is disposed in the bobbin chamber and reversely bent at 26 to form the spring end portions 27 which converge at the point 28 where the 25 ends meet to provide a tension passageway for the filling as it is drawn from the filling carrier or bobbin. In the modified construction, as in the preferred form of the invention, it will be noted that the spring tensioning members are not only located in the 30 bobbin chamber but enclose the end portion of the filling carrier or bobbin 4, and their meeting ends rest upon the support 16 beneath.

45 As indicated in Figs. 2 and 5, the projections or lugs 20 above the rest or support 16 are located one at each side of the spring tensioning plates and serve as stops for any excessive separating movement of such 50 plates which might tend to destroy their resiliency.

What is claimed is:

1. An automatically threading loom shuttle having a bobbin chamber, two leaf springs extending longitudinally of the shuttle and converging within the bobbin chamber to enclose the end portion of the bobbin and prevent ballooning and to provide tension on the thread as it unwinds from the bobbin during weaving.
2. An automatically threading loom shut-

tle having a bobbin chamber and threading block, two leaf springs secured to the shuttle with their thread tensioning ends inclosing the end of the bobbin within the bobbin chamber rearward of the threading block, and a shelf extending into the bobbin chamber and supporting the tensioning ends of the springs frontward of the end of the bobbin.

3. An automatically threading loom shuttle having a bobbin chamber and threading block, two leaf springs secured to the shuttle with their thread tensioning ends inclosing the end of the bobbin within the bobbin chamber rearward of the tensioning block, means for adjusting the ends of the springs relatively towards and from each other, and a shelf extending into the bobbin chamber and supporting the tensioning ends of the springs frontward of the end of the bobbin.

4. An automatically threading loom shuttle having an open bobbin chamber, a threading block frontward of the bobbin chamber, two leaf springs secured to the shuttle and extending longitudinally in the bobbin chamber, the ends of said springs converging frontwardly and inclosing the end of the bobbin rearward of the threading block, and a shelf extending rearwardly from the end of the shuttle into the bobbin chamber for supporting the ends of the springs.

5. An automatically threading loom shuttle having an open bobbin chamber, a threading block frontward of the bobbin chamber, two leaf springs secured to the shuttle and extending longitudinally in the bobbin chamber, the ends of said springs converging frontwardly and inclosing the end of the bobbin rearward of the threading block, a shelf extending rearwardly from the end of the shuttle into the bobbin chamber for supporting the ends of the springs, and means for adjusting the tensioning effect of the springs.

6. An automatically threading loom shuttle having a bobbin chamber, two leaf springs extending longitudinally of the shuttle within the bobbin chamber and converging about the end of the bobbin in the bobbin chamber to prevent excessive ballooning of the thread and provide tension thereon during weaving, the upper edges of the converging leaf springs being inclined frontwardly and transversely of the bobbin chamber adjacent the delivery end of the bobbin.

In testimony whereof, I have signed my name to this specification.

WILLIAM R. THIGPEN.
